[57] CLAIM

The ornamental design for a multi-picture display frame, substantially as shown and described.

DESCRIPTION

FIG. 1 is a perspective view of a multi-picture display frame showing my new design with the front, top and left side thereof visible;

FIG. 2 is a front elevation view thereof;

FIG. 3 is a back elevation view thereof;

FIG. 4 is a top plan view thereof with the appearance from the bottom being substantially the same; and

FIG. 5 is an elevation view of the right side thereof with the view from the left being substantially similar.

FIG. 1

FIG. 2

FIG. 3

FIG. 4

FIG. 5
